CONTAINER FOR CIGARS OR THE LIKE

Edward G. Brandwein, Chicago, Ill., assignor to
 Crystal Tube Mfg. Co., Chicago, Ill., a corpora-
 tion of Illinois

Application April 20, 1936, Serial No. 75,264

2 Claims. (Cl. 131—11)

The invention relates to containers for cigars or similar articles and more particularly to such containers made of flexible transparent cellulose material such as "Cellophane".

5 Material of this type has many characteristics which especially adapt it for use as a wrapping for cigars or similar articles. Thus it is transparent so that the contained article may be readily viewed by the purchaser, it may be readily sealed to maintain the moisture content of the article, and it is economical to manufacture. On the other hand, such cellulose material is very tough and difficulty has heretofore been experienced in removing it, especially from cigars, since 10 the wrapper ordinarily fits snugly about the same so that it is difficult to pinch or tear the wrapper without injuring the cigar. In addition, cigars are comparatively brittle and subject to damage in case they are roughly handled by an exasperated user in attempting to remove the cellulose 15 wrapper or container.

The principal object of the invention is to provide a container for cigars or the like made of a transparent flexible cellulose material and 20 so constructed that it may be readily removed from the cigar or the like without danger of injury to the latter.

More specifically, it is an object of the invention to provide a container of the type described 25 having a tearing thread held in position therein by the adhesive which holds the longitudinal edges of the container together, with one end of the thread projecting freely from the container in a position to be readily grasped for pulling the same longitudinally with respect to the container 30 to tear open the side thereof.

Further objects and advantages of the invention will become apparent as the following description proceeds and the features of novelty 35 40 which characterize the invention are pointed out with particularity in the claims annexed to and forming a part of this specification.

For a better understanding of the invention reference may be had to the accompanying drawing in which,

Figure 1 is a perspective view of a cigar enclosed by a container embodying the invention.

Fig. 2 is a perspective view of the cigar and 50 container shown in Fig. 1, the upper end of the container being shown in its open position prior to sealing the same.

Fig. 3 illustrates the method of utilizing the tearing thread to open the side of the container.

55 Fig. 4 is an enlarged side elevation of the con-

tainer shown in Fig. 1 prior to the insertion of a cigar therein.

Fig. 5 is a sectional view along the line 5—5 of the container shown in Fig. 4.

In the exemplary form shown in the drawing 5 the invention is embodied in a wrapper or container 10 enclosing a cigar 11. The wrapper 10 is made from a substantially rectangular sheet of tough flexible transparent cellulose material such as "Cellophane". As best shown in Fig. 5, the 10 longitudinal edges of the sheet are arranged in overlapping relation and secured together by a thin layer of transparent adhesive 12. An elongated tube or cylinder is thus formed. This tube 15 is preferably flattened by forming longitudinally extending re-entrant folds 13 and 14 in the side walls thereof in order to give the container a convenient shape for shipping or handling prior to the insertion of a cigar therein.

The lower end of the tubular container thus 20 formed is closed by doubling one end portion of the tube back upon itself and securing it in this position by a layer of transparent adhesive as indicated at 15 in Figs. 1 to 4, inclusive. The opposite end of the tubular container 10 is left 25 open in order that a cigar may be readily inserted therein.

In accordance with the invention, an arrangement has been provided for tearing a side wall of the wrapper 10 so that the cigar 11 may be 30 readily removed. This arrangement preferably includes a tearing thread 16 positioned within the container 10 and extending longitudinally thereof. As best shown in Fig. 5, the tearing 35 thread 16 is preferably positioned between the overlapping portions of the sheet of cellulose material which forms the container and extends along the inner edge of the layer 12 of adhesive. The adhesive thus serves to hold the thread 16 in 40 position. The lower end of the tearing thread 16 extends within the doubled end portion 15 of the container 10 and is held against longitudinal movement thereby.

The opposite or upper end of the tearing thread 45 16 extends freely from the container in a position to be readily grasped for pulling the same longitudinally with respect to the container to tear open the side thereof. Thus, a thumb notch 17 is preferably formed at the upper end of the container 10 in alignment with the overlapping 50 longitudinal edges thereof and the upper end 18 of the tearing thread 16 extends freely through this notch. When the upper end of the container 10 is folded back on itself and sealed in such position as indicated in Fig. 1, the end 18 of the 55

tearing thread 16 is still freely exposed so that it may be readily grasped by the user.

- In opening the container 10, the cigar may be held in one hand as indicated in Fig. 3 while the tearing thread 16 is pulled longitudinally from the container, thus tearing a longitudinal slit in the side wall of the container so that the cigar may be removed therefrom. It will be seen that in the particular construction illustrated, only the upper one of the overlapping longitudinal edge portions of the container need be torn in order to completely separate the same since the adhesive 12 is located entirely at one side of the tearing thread 16.
- 15 While a particular embodiment of the invention has been shown in the form of a wrapper for a cigar, it will be understood that no intention should be inferred to limit the invention to the particular construction shown and described but,
- 20 on the other hand, it is intended in the appended claims to cover all modifications within the spirit and scope of the invention.

I claim as my invention:

1. An elongated container for a cigar or the like comprising a tube formed from a tough flexible transparent sheet of cellulose material with the longitudinal edges thereof arranged in overlapping relation and secured together by a thin layer of transparent adhesive, and a tearing

thread positioned within said tube between said overlapped longitudinal edges in contact with a longitudinal edge portion only of said layer of adhesive substantially throughout its length, one end portion of said tube being doubled upon itself 5 and secured in position by a layer of transparent adhesive to close the end of the container, the corresponding end of said tearing thread being held securely within said doubled end portion, the opposite end of said tube having a notch 10 formed therein with the adjacent end of said thread extending freely therethrough in a position to be readily grasped for pulling the same longitudinally with respect to said tube to tear open the side thereof. 15

2. A container comprising a tube formed from a tough flexible transparent sheet of cellulose material with the longitudinal edges thereof arranged in overlapping relation and secured together by a thin layer of transparent adhesive, 20 and a tearing thread positioned within said tube along the underlying one of said overlapped longitudinal edges in contact with the edge portion only of said layer of adhesive substantially throughout its length, one end of said thread projecting freely from said tube in a position to be readily grasped for pulling the same longitudinally with respect to said tube to tear open the side thereof. 25

EDWARD G. BRANDWEIN. 30
